UNITED STATES PATENT OFFICE.

GEORGE W. WRIGHT, OF LAPEL, INDIANA.

MIXER AND VAPORIZER.

No. 922,374.

Specification of Letters Patent.

Patented May 18, 1909.

Application filed December 26, 1908. Serial No. 469,499.

To all whom it may concern:

Be it known that I, GEORGE W. WRIGHT, a citizen of the United States, residing at Lapel, in the county of Madison and State of Indiana, have invented certain new and useful Improvements in Mixers and Vaporizers; and I do declare the following to be a full, clear, and exact description of the invention, reference being had to the accompanying drawings, and to the letters and figures of reference marked thereon, which form a part of this specification.

This invention relates to apparatus for feeding liquid and for mixing and vaporizing the liquid with air, especially for mixing and vaporizing gasoline with atmospheric air, or for mixing gas or alcohol with air, to produce gaseous or hydrocarbon fluid for use in explosive engines, the invention having reference particularly to improved means whereby the liquid is fed and vaporized with the air.

The object of the invention is to provide an improved mixer and vaporizer of the above-mentioned character of compact form and which may be manufactured cheaply, and be durable, efficient and economical in use.

With the above-mentioned and other objects in view the invention consists in an improved mixer and vaporizer comprising a case having a centrally disposed valve-seat body member therein, on which is an externally arranged annular valve-seat, and in which are feed ducts terminating or having their outlet orifices in the valve seat, a valve for regulating the flow of liquid through the ducts, and a combined valve and vaporizer operating as a piston in the case and having an internally arranged valve face normally seated on the valve-seat and covering the feed ducts, all of novel construction and arrangement; and the invention consists further in the parts and combinations and arrangements of parts as hereinafter particularly described and then defined in the accompanying claims.

Referring to the drawings Figure 1 is an elevation of the improved mixer and vaporizer; Fig. 2, a longitudinal sectional view on the line A A in Fig. 1; Fig. 3, an end view or top plan of Fig. 1 partially broken away; Fig. 4, an elevation or side view of the combined valve and vaporizer partially in section; Fig. 5, a transverse sectional view on the line B B in Fig. 2 partially broken away; Fig. 6, a fragmentary perspective view of the

portion having the valve-seat body member therein; Fig. 7, an end or plan view of the combined valve and vaporizer slightly modified; and Fig. 8, a top plan of the portion of the case having the valve-seat body member therein slightly modified.

Similar reference characters in the drawings indicate corresponding elements or features of construction referred to herein.

As preferably constructed the case of the mixer and vaporizer comprises a number of sections of circular form and suitably jointed and fitted together, there being an inlet end section 1 having internal screw-threads 2 and external lugs 3, the section being designed to receive the atmospheric air and to be connected to an air inlet pipe, if desired. A middle section 4 is joined to the section 1, and an end section 5 is joined to the section 4 and has external lugs 6, the three sections being held together rigidly by a suitable number of bolts 7 connected with the lugs 3 and 6. The outlet or upper end of the section 5 has external screw-threads 8 thereon whereby the case may be connected tightly to the cylinder or explosion chest of an engine or to a pipe. The case may be arranged either in upright position, as shown, or at any angle to the perpendicular that may be desired without detracting from the efficiency of the apparatus in operation, but for the purposes of description the apparatus is considered as being vertical or with its longitudinal axis in vertical arrangement.

The middle section 4 of the case has a circular valve seat body member 9 supported centrally therein by means of arms 10, 11, 12, cast integrally therewith, so that air may pass between the wall of the case and the valve seat body member, the latter having a vertical duct 13 therein extending centrally from the top toward the bottom thereof, and an annular valve-seat 14 is formed on the upper edge portion of the body member, so as to be like the frustum of the cone in shape on its face, or beveled, the valve-seat preferably having a small annular groove 15 in its face, a suitable number of feed ports as 16, 16', 16'', being formed in the body member in communication with the duct 13 and terminating in the valve-seat 14 or in the groove 15, the feed ducts being arranged radially to the axis of the duct 13 and inclined thereto, so as to extend approximately at right angles to the plane of the face of the valve-seat 14. The ducts are

preferably formed by drilling, after which the upper end of the duct 13 is closed by a plug 17 or otherwise, as may be desired. The section 4 of the case has a branch 18 formed thereon that extends laterally from the exterior opposite the arm 10, and has a chamber 19 therein that extends through the wall of the case section and into the valve seat body member 9 nearly to the duct 13, there being a valve-seat 20 formed at the inner end of the chamber from which extends a relatively short duct 21 that communicates with the duct 13. The branch 18 has a nipple 22 formed thereon in which is a passageway 23 communicating with the chamber 19 to receive the liquid or a gaseous fluid, the nipple having external screw-threads 24 for connecting a supply pipe thereto. A valve-stem 25 having screw-threads 25' is screwed into the branch 18 and has a needle point valve 26 on its inner end that operates in connection with the valve-seat 20, the outer end of the valve-stem having a hand-wheel 27 thereon, and a packing nut 28 is employed to prevent leakage of the liquid from the chamber 19.

The upper or outer end of the section 5 of the case has a valve-stem guide 29 supported therein by integral arms 30 for assisting to guide the combined valve and vaporizer which comprises an annular body part 31 that is fitted closely and is movable as a piston against the inner side of the wall of the case, and in some cases is provided with a packing ring 32 to prevent the passage of air past the valve-body. The under side of the valve-body has an internal annular beveled valve face 33 formed at the inner side thereof to correspond with the contour of the valve-seat 14 and normally rests thereon, the valve-face 33 preferably having an annular groove 34 therein that registers with the groove 15 in the valve-seat, the two grooves together forming a channel which forms communication between all the feed parts 16, or 16', so that in some cases the liquid may fill the channel while the valve is closed, and obviously, if desired, the valve-seat 14 may be made without a groove 15, and also the groove 34 may be omitted, the plain valve face and seat being shown in Figs. 7 and 8; or the groove may be made in only one part either in the valve-seat or in the valve-face.

The valve-body has a flange or skirt extending from and below the underside 31' of the valve-body, and it extends against the inner side of the case, so that the under side of the valve-body is practically cup shaped to induce the air to flow through the opening 36 of the valve-body rather than past the outer side of the body. A suitable number of posts 37 are formed on the top or upper side of the valve-body, and a disk 38 is formed on the tops thereof that preferably has a conical shaped under side 39 to deflect

and assist in vaporizing the liquid, the upper side of the disk 38 having a stem 40 thereon that is guided in the guide 29, and preferably has a shoulder 41 adapted to engage the guide when the valve is lifted excessively, the valve being normally held on its seat to cover the ports by a spring 42 extending about the stem 40 and seated against the disk 38 and the guide 29.

In practical use the valve wheel 27 will be turned to admit liquid from the chamber 19 into the duct 21, from which the liquid will flow through the duct 13 and through the ports as 16 to the face 33 of the valve and into the grooves that may be formed in the valve face and the valve seat where the liquid will be confined until released by unseating the valve. During the movements of the explosive engine the piston in the engine cylinder will at intervals produce a partial vacuum in the outlet end of the case of the mixer and vaporizer, so that the atmospheric pressure exerted against the under side 31' of the valve-body will lift the valve from its seat and permit the air to rush through between the valve and the seat and take with it the liquid that may be in the channel above-mentioned or in the orifices of the feed-ports, the in-rushing air tending to atomize the liquid which is drawn violently against the under side 39 of the disk 38 by which it is deflected against the wall of the case, being thereby further broken up or vaporized, the liquid becoming still more vaporized in its passage with the air past the arms 30 and into the engine cylinder or explosion chamber thereof.

It will be understood, of course, that the mixer and vaporizer may be used for other purposes than that described and obviously may be operated otherwise than by section or vacuum, as for instance the air may be supplied in impulses by an air pump for lifting the valve and vaporizing the liquid.

Having thus described the invention, what is claimed as new, is—

1. A mixer and vaporizer including a case, a valve seat body member in the case having a beveled end forming an external valve-seat thereon, the body member having a duct therein and also a plurality of feed-ports radiating from the duct to the valve-seat, a hollow arm extending from the wall of the case to said member forming a passageway to the duct, there being space between said member and the wall of the case, and an annular valve body having an internal valve face normally engaging the valve seat and closing the feed-ports, the valve body forming a piston in contact with the case and normally closing the space between said valve seat body member and the case.

2. A mixer and vaporizer including a case having a valve seat body member rigidly supported therein with clear space about one

- end of said member between said member and the case, the end of said member having an annular valve-seat thereon, said member having a duct therein and also a plurality of 5 feed-ports radiating from the duct to the valve-seat, an annular valve body having a valve face at the inner side thereof that normally engages the valve-seat and closes the feed-ports, the valve body extending across 10 the space between said member and the case and forming a piston in contact with the case, the valve body having posts thereon, a disk on the posts, and a spring seated in the case and normally holding the valve face to the 15 valve-seat.
3. A mixer and vaporizer including a case, a valve seat therein having a plurality of feed-ports extending convergently therefrom, a duct in communication with the 20 feed-ports, and an annular valve having a face normally engaging the valve seat and covering the orifices of the feed-ports, the valve face having a groove therein forming communication along the valve-seat between 25 the feed-ports, the body of the valve forming a piston in contact with the case.
4. A mixer and vaporizer including a case having a valve-stem guide, a valve seat body member fixedly supported in the case and 30 having an annular valve seat thereon, the body member having a duct therein and also a plurality of feed-ports radiating from the duct to the valve seat, an annular valve body having a face normally engaging the valve 35 seat and closing the feed-ports, the valve body forming a piston in contact with the case, the valve body having posts thereon, a disk formed on the posts, a stem on the disk engaging the guide, and a spring seated in 40 the disk and against the guide.
5. A mixer and vaporizer comprising a case having a branch thereon in which is a chamber, a valve seat body member having an arm thereon that is formed integral with 45 the wall of the case opposite the branch and having said chamber extending therethrough, said seat body having said chamber extending therein and having a valve seat at the inner end of said chamber and also a duct extending from the valve seat transversely to 50 the case in said seat body, said seat body having a longitudinal duct therein extending from said transverse duct and having also an annular valve seat thereon and a plurality of feed-ports extending radially from the longitudinal duct to the valve seat, an annular valve body having a face normally engaging the annular valve seat and closing the feed-ports, said valve body forming a piston in contact with the case, and a valve stem 60 mounted in said branch and extending through said chamber and having a valve thereon coöperating with the valve-seat that is formed at the inner end of said chamber.
6. In a mixer and vaporizer, the combination with a case, and a valve seat body member mounted fixedly in the case with space between the case and the body member, the body member having an annular valve seat thereon and having also an opening there- 65 through for the passage of liquid, of a combined valve and vaporizer comprising an annular valve body forming a piston in engagement with the case, the valve body having an annular valve face normally seated on the 70 valve seat, the valve body extending across said space and having a flange extending about the valve seat body member and against the case, said valve body having posts thereon, and a deflecting disk on the 75 posts opposite to the valve seat body member.
- In testimony whereof, I affix my signature in presence of two witnesses.
